UNITED STATES PATENT OFFICE.

CHARLES N. SCHULER, OF CHICAGO, ILLINOIS, ASSIGNOR TO PETER VAN SCHAACK & SONS, OF CHICAGO, ILLINOIS, A CORPORATION OF ILLINOIS.

LEATHER ARTICLE.

1,182,217.

Specification of Letters Patent.

Patented May 9, 1916.

Application filed October 15, 1915. Serial No. 56,128.

To all whom it may concern:

Be it known that I, CHARLES N. SCHULER, a citizen of the United States, and a resident of Chicago, county of Cook, and State of Illinois, have invented a certain new, useful, and Improved Leather Article, of which the following is a specification.

My invention relates generally to an improved article of manufacture composed of 10 pieces of leather.

The general object of my invention is to provide means whereby it shall be possible to utilize portions of the hide, particularly 15 hides of a soft, pliable nature, of which the chamois is an example, which have hitherto been considered scrap material, and of little or no commercial value.

Another object of my invention is to provide an article of manufacture for utilizing 20 such scrap or waste material which can be made with simple mechanism; which can be made by unskilled labor; which shall be of low cost; and which shall be of such character that it shall serve effectually the 25 purpose for which it has been hitherto necessary to use a much more expensive article.

Leather of soft, tough, and pliable nature, such as was first made from the chamois 30 hide, but which at the present time is made from the hides of the chamois, sheep, and many other animals, is used in vast quantities in many industries and for various purposes. One very well known purpose for 35 which such leather is used is that of a wiping, rubbing, or polishing element. Because of its tough, compact, but extremely soft and pliable character, it is by far the best suited for many classes of the work, and for 40 some classes of work can hardly be dispensed with. In short, the modern uses of chamois are so many and varied, and the demand so great, that the cost thereof is very high. The terms chamois, the chamois, 45 etc., as herein used are to be construed to mean all leathers of chamois-like nature. The chamois skin or hide, like other hides, is extremely irregular in shape, and it is customary to cut from the hide regularly 50 shaped pieces of various sizes and shapes to suit the different commercial requirements. In the cutting of these somewhat regular shapes from the extremely irregular hide, many scrap or waste portions of varying 55 sizes and shapes remain. These scrap por-

tions have hitherto had little or no commercial value and have practically been considered waste material. I have devised an article of manufacture for utilizing such irregular scrap or waste portions, whereby 60 they will serve just as well for a great many purposes as the much more expensive regular shapes and sizes. I thus turn a practically worthless product into articles of great utility and of large commercial value. 65

My invention consists generally in an article of manufacture for accomplishing the aforementioned objects, as well as other objects which will appear hereinafter, and my invention will be more readily understood 70 by reference to the accompanying drawings which illustrate preferred embodiments thereof, and wherein—

Figure 1 represents a hide or skin of chamois leather, the lines of severance being 75 indicated; Fig. 2 represents a number of the scrap or waste portions resulting from the division of the hide; Fig. 3 represents selected particles of the scrap or waste material arranged in proximate relation; Fig. 80 4 represents a tie member; Fig. 5 is a view similar to Fig. 3, but indicating the scrap pieces tied together; Fig. 6 indicates the article of Fig. 5 somewhat bunched or padded and as it is often used in wiping, 85 rubbing, or polishing operations; Fig. 7 illustrates a modified article of manufacture embodying my invention; Fig. 8 illustrates another modified article embodying my invention; Fig. 9 illustrates a further modified 90 article embodying my invention; and Fig. 10 illustrates a still further modified article embodying my invention.

In Fig. 1 of the drawings I have indicated in a somewhat general way a hide 2, 95 the outer edge of which it will be noted is extremely irregular. From the hide 2, it has hitherto been customary, for many commercial purposes, to cut somewhat regularly sized and shaped pieces, as indicated by the 100 substantially rectangular divisions 3. I have indicated the lines of severance in only a general way, and along only one side of the hide, but it will of course be understood that the rest of the hide is also cut up into 105 similar or desired sizes and shapes. In cutting the hide into such shapes and sizes it will be noted that many irregular shaped portions 4, of various sizes and shapes remain. These detached remaining portions 110

4, a number of which are depicted generally in Fig. 2, have hitherto been considered scrap or waste material and of little or no commercial value. For example, the regular sizes and shapes sell by the piece at a good price, while these so called scrap or waste portions sell by the ton for a few dollars a ton. The reason for this prevailing condition is that hitherto no one, to the best of my wide knowledge on the subject, has found a commercially practicable method of utilizing such pieces for the purpose for which chamois is most valuable, to-wit: as a wiping, rubbing, or polishing element.

I shall now describe in detail the manner in which I have solved the problem. I divide the hide in the usual manner, thereby securing the usual many scrap portions 4. I then choose from the scrap portions the desired ones, preferably, though not necessarily, those which bear some convenient relation to each other as to size, and arrange the chosen pieces in proximate relation as is indicated, on a somewhat enlarged scale, in Fig. 3. After I have thus chosen and arranged the pieces, I secure them together by any suitable means. However, I find it desirable that the means employed should be of such character that while it serves to bind the pieces firmly together so that all the pieces of a given group will move as a unit, nevertheless, the pieces must be sufficiently free that they can be conveniently bunched or compacted to form an efficient, wiping, rubbing, or polishing pad. This very desirable result I find that I can produce by binding the parts together with a tie band (illustrated in Fig. 4 and marked with the numeral 5). I place the tie band 5 upon the proximately arranged chamois pieces and secure it thereto preferably by sewing as indicated at 6 in Fig. 5. Operating in this way the chamois pieces can be quickly assembled and sewed or otherwise secured together and an article of manufacture produced at a low total cost which will serve as efficiently for a wiping, polishing, or rubbing pad as the much more expensive single piece article. In using the article which I have thus produced for wiping, polishing, or rubbing, I find it convenient to gather the parts into a somewhat compact bunch or pad, as indicated in Fig. 6. This can be quickly and easily done when the article is picked up in the hand for use. The tie band 5 I make of a strong, tough, but relatively soft material, so that there is no danger of scratching or injuring the surface operated upon. In use, however, the tie member is practically surrounded by the chamois pieces so that it seldom if ever comes into contact with the surface acted upon. Instead of tying the members 4 together by means of a tie band as indicated in Figs. 5

and 6, I may arrange the chamois pieces so that each piece overlaps the next adjacent one and then sew the parts together. I have indicated such a construction in Fig. 7 wherein the parts 4 have overlapping parts 6 which are secured to the adjacent piece by means of sewing or stitching 7.

It will be noted that the articles of manufacture thus far described as resulting from my improved method, assume a general longitudinal extension, but I wish it to be understood that I may arrange the pieces in other forms. For example, I may arrange the pieces so that the resulting article, when tied together, shall be nearly square in shape. I have indicated such a construction in Fig. 8, wherein 4 indicates the scrap chamois pieces which in this instance I arrange in a longitudinal row and a transverse row and secure the rows together by interconnecting longitudinal and transverse tie members 5.

I have discovered that a single strong tie member serves admirably to hold the pieces together; that it can be quickly applied to the assembled chamois pieces by unskilled laborers; and that it produces a satisfactory article, the total cost of which is much lower than that of a single similar sized piece of chamois. I find also that a strong cloth tape or tie member is a very satisfactory element for holding the chamois pieces together. I may, however, secure the chamois pieces together by several tie bands which may be of other or desired material. For example, it is within the province of my invention to tie the pieces together by means of scrap leather. I have indicated such a construction in Fig. 9, wherein 4 represents the usual scrap chamois arranged in desired proximate relations in the manner already described and secured together by a plurality of bands 10 formed of scrap leather. By this construction the complete article is composed of chamois leather so that there is not even a remote danger of marring or injuring the surface acted upon.

Under certain conditions I find it desirable in securing the scrap pieces together to both overlap the adjacent pieces and to tie all the parts together by means of a strong tie member. Such a construction is advisable when it is desirable to use quite small pieces. I have illustrated such a construction in Fig. 10, wherein 4 represents the scrap chamois pieces, which are so arranged that portions 14 thereof overlap the pieces next adjacent. On the entire number of pieces forming the article, I secure a tie member 15 by suitable means such as stitching 16. This construction forms a very strongly bound completed article in which even relatively small chamois pieces may be advantageously used.

From the foregoing detailed description it

is thought that the object, purposes, and advantages of my invention will be fully understood by those skilled in the art to which it appertains, but inasmuch as this disclosure will readily suggest to others modified articles whereby the substantial objects of my invention may be attained, I do not wish to be limited to the specific constructions herein described except as may be necessary 10 by express limitations in the hereunto appended claims.

I claim:

1. An article of manufacture, comprising a plurality of scrap chamois pieces, of substantially the same length arranged in proximate relation and a relatively narrow single strong tie band sewed centrally to and connecting all of the pieces.

2. A ³ article of manufacture comprising a plurality of scrap chamois pieces, arranged in proximate relation with a portion of each piece overlapping the piece next adjacent, and a single tie band sewed to all of the pieces. 20

3. An article of manufacture comprising a plurality of scrap chamois pieces arranged in proximate relation and a relatively narrow tie band secured to and connecting all of the pieces. 25

In testimony whereof, I have hereunto set my hand, this 4th day of October, 1915, in the presence of two subscribing witnesses.

CHARLES N. SCHULER.
